UNITED STATES PATENT OFFICE.

WILLIAM F. LEACH, OF ST. CLAIR, MICHIGAN, ASSIGNOR TO B. F. CRAMPTON, OF SAME PLACE.

PORTABLE STEAM-AUGER.

SPECIFICATION forming part of Letters Patent No. 271,480, dated January 30, 1883.

Application filed April 26, 1882. (No model.)

To all whom it may concern:

Be it known that I, WILLIAM F. LEACH, of St. Clair, in the county of St. Clair and State of Michigan, have invented new and useful 5 Improvements in Portable Steam-Augers; and I do hereby declare that the following is a full, clear, and exact description thereof, reference being had to the accompanying drawings, which form a part of this specification. 10 The nature of this invention relates to certain new and useful improvements in the construction of portable steam-augers, and is especially designed as an improvement upon a device of that character patented to me July 15 1881, No. 244,629.

The invention consists in the peculiar combination of mechanism by means of which the speed of the auger is regulated, and also in the means provided for handling the device, 20 and in the combination and operation of the various parts, as more fully hereinafter described.

In the accompanying drawings, wherein my invention is shown in elevation in Figure 1 25 and in an end view in Fig. 2, A represents the shaft of a rotary engine, B, which latter may be of any of the known constructions. Sleeved upon the stuffing or journal box of this shaft is the hub D, adjustably secured in 30 place by the set-screw a upon the shaft-bearing f, rigid with and projecting from the main frame of the engine, and provided with an arm, b, which carries the counter-shaft E in such manner as to allow the same to revolve.

Upon the shaft A is adjustably secured, by any of the known means, the pinion C, designed to communicate motion to the shaft E through the pinion F, which is also adjustably secured upon the shaft E; in the end of 40 which is provided a socket, c, to receive the shaft of an auger, which, when inserted, is secured therein by the set-screws d. By this arrangement, the speed of the engine being known, as well as the required speed of the auger, which latter it is desired to change with various descriptions of work, the changing of the pinions upon the shaft and counter-shaft to correspond will enable the operator to increase or diminish the speed of his auger-shaft

without changing the speed of the engine-shaft. The opposite end of this shaft runs in a box or bearing, upon which there is sleeved a short length of gas-pipe, h, secured by set-screws i. The free end of this gas-pipe terminates in a T-head, K, secured to said gas-pipe 55 by means of a set-screw, k; or any other convenient form of handle may be attached for the purpose of allowing the operator or operators to more readily handle the device in any position where it may be necessary to use the 60 auger.

The manner of using my invention is as follows: The speed at which the auger is to be driven having been regulated by the relative size of gears C F, the operator adjusts the collar 65 D and arm b to the desired position by the set-screws a, and holds the device in the desired position by the handle K. Steam then being admitted into the engine, the shaft A turns, and, by means of the gears C F, rotates the 70 counter-shaft E in the opposite direction, and thereby imparts motion to an auger held in the socket at the end of the counter-shaft.

Having described my invention, what I claim as new, and desire to secure by Letters Patent, 75 is—

1. The combination, with a rotary engine and the shaft thereof, of a movable bearing constructed to be adjusted around said shaft, a second shaft adapted to carry an auger and 80 revolving in said adjustable bearing, and gear-wheels transferring the motion of the shaft of the engine to the shaft revolving in the adjustable bearing, substantially as and for the purpose specified. 85

2. The combination, with a rotary engine and the journal-box f thereof, of the hub D, carrying the arm b, constructed to be adjusted around said box, and a second shaft adapted 90 to carry an auger and revolving in said adjustable arm, both shafts being provided with gear-wheels meshing with each other, all constructed and arranged substantially as and for the purpose specified.

WILLIAM F. LEACH.
